UNITED STATES PATENT OFFICE

2,423,386

TWO-TEMPERATURE REFRIGERATING SYSTEM

Earl F. Hubacker, Highland Park, Mich., assignor
to Borg-Warner Corporation, Chicago, Ill., a
corporation of Illinois

Application February 21, 1944, Serial No. 523,280

6 Claims. (Cl. 62—115)

1

This invention relates to refrigeration, and it has particular reference to a refrigerating system that is adapted for household or domestic use. The present improvements are especially directed to a refrigerating system for producing multi-temperatures in a plurality of separate refrigerating compartments wherein different temperatures are maintained.

It is one of the principal objects of the present invention to simplify the construction of a multi-temperature refrigerating system such as contemplated herein, and to improve the efficiency, operation, and dependability of such system.

Also it is a principal object of this invention to provide, in a multi-stage refrigerating system, an arrangement wherein a high-pressure vapor from a high-temperature evaporator is returned to a compressor that is common to a low-temperature evaporator, the said evaporators being individual to the respective refrigerating compartments wherein different temperatures are maintained. In this connection it is a further object hereof to provide a two-suction rotary compressor assembly wherein the high-pressure suction inlet from a high-temperature evaporator is maintained at a higher pressure than the low-pressure suction inlet from the low-temperature evaporator.

Still another object of this invention is to provide a refrigerating system of the character herein contemplated wherein a capillary tube is interposed in the line between a condenser and a high-temperature evaporator, such capillary tube adapted to perform the function of a choke coil to effect a constant throttle upon the fluid.

A further object hereof resides in providing a capillary member or choke tube coil between the high and low temperature evaporators of a refrigerating system to effectively meter the fluid as it flows between the respective evaporators.

A still further object of this invention is to provide simple metering means in the respective high-pressure and low-pressure conduits to control the flow of refrigerant to the respective high-temperature and low-temperature evaporators, such metering means comprising capillary tubes that are calibrated to the specific requirements of a particular installation as to the capacities of the respective refrigerating chambers or compartments.

Additional objects, aims, and advantages of the invention contemplated herein will be apparent to persons skilled in the art after the construction and operation of the multi-temperature refrig-

2

erating system is understood from the within description.

It is preferred to accomplish the numerous objects of this invention and to practice the same in substantially the manner hereinafter fully described and as more particularly pointed out in the appended claims, reference being made to the accompanying drawings that form a part of this specification, wherein:

10 Fig. 1 is a view in diagrammatic form showing the instrumentalities of this multi-temperature refrigerating system; and

15 Fig. 2 is a view, somewhat schematically drawn, of a unitary double-suction compressor such as utilized in the refrigerating system contemplated herein.

20 The drawings are to be understood as being more or less of a schematic character for the purpose of disclosing a typical or preferred embodiment of the improvements contemplated herein, and in these drawings like reference characters identify the same parts in the several views.

25 The multi-temperature refrigerating system contemplated herein preferably comprises two chambers or compartments shown in broken lines, A and B, in which different temperatures are to be maintained. The chamber B may be termed the so-called "deep-freeze" or "quick freeze" low-temperature compartment of a household refrigerator, while the other chamber A is the normal cold compartment wherein the temperature is higher than in the deep-freeze compartment B. Both of the chambers A and B, as well as the other instrumentalities of this refrigerating system shown in Fig. 1, are enclosed within the usual refrigerator cabinet which is not illustrated since it forms no portion of the present invention.

30 The refrigerating agent, preferably methyl-chloride (CH_3Cl), is raised to a high pressure in the compressor 5 from which it is discharged through the outlet port 6 into a pipe 7 that leads to a condenser coil 8 where the gas becomes liquified. The compressor 5 is a unitary double-suction arrangement of the rotary type to create 35 high pressure upon the refrigerating agent for forcing it through the closed insulating conduits or lines that pass through the respective chambers or compartments A and B. The high-pressure suction line or return conduit 9 leads into 40 the compressor through the high pressure suction port 10 to return refrigerant to the compressor from the high-temperature chamber A, and a low-pressure suction line or conduit 11 leads into the compressor through the low-pressure suction port 12 to return refrigerant from the low-

temperature chamber B to the compressor. The porting arrangement of the unitary compressor is such that the low-pressure suction port 12 is open to the compressor cylinder at all times, while the high-pressure suction port 10 is opened only when the rotor has completed a portion or approximately 50% to 60% of its stroke and thereafter the refrigerant from the high-pressure suction line 9 will be admitted to the compressor cylinder during the remainder of the stroke of the rotor. The effect of this arrangement is that the high-pressure suction inlet of the compressor is maintained at a higher pressure than the low-pressure suction inlet that receives the refrigerant returning from the low-temperature or deep-freeze chamber B.

Upon leaving the condenser 8 the liquified refrigerant passes through a capillary member 13 that communicates at one end with said condenser and at its other end discharges into a high-temperature evaporator coil 14 within the chamber A that is to be maintained at a temperature above that in the deep-freeze chamber B. The capillary member 13 is preferably a coiled tube having a small internal diameter or bore that is calibrated to predetermined dimensions depending upon the particular requirement for refrigerant in the evaporator 14. The capillary member 13 acts as a choke tube coil to throttle the flowing refrigerant and meter the liquid to the high-temperature evaporator in the quantity that is needed by the latter. This action is attributed to the well-known phenomenon of physics which is associated with surface tension and angle of contact, an example of which is the rise of liquids in a wick or tube. The evaporator 14 effects a vaporization of a portion of the liquid refrigerant and the vapor so liberated is withdrawn from the evaporator into high-pressure suction line 9 through which this withdrawn vapor is returned to the compressor 5.

The liquid portion of the refrigerant in the high-temperature evaporator 14 that remains after the vapor has left said evaporator is discharged into an overflow pipe 15 from which it passes through a low-pressure capillary member 16 that is interposed between said pipe and the low-temperature evaporator 17 in the deep-freeze chamber B. The capillary member 16 is preferably similar to the high-pressure capillary member 13, and it provides a constant throttle upon the liquid refrigerant to meter its feed to the deep-freeze or low-temperature evaporator 17. The vaporized refrigerant leaves the low-temperature evaporator through the low-pressure suction line or conduit 11 and is returned to the compressor 5 through the low-pressure suction port 12.

Check-valves or similar devices are provided in both suction return lines. A check valve 18 is interposed in the low-pressure suction return pipe 11 and it is placed close to the compressor or cylinder to reduce re-expansion volume to a minimum. In the high-pressure suction return pipe 9 a check-valve 19 is located at a convenient place to prevent oil and extraneous matter working up into the evaporator 14.

In the two-temperature or multi-stage refrigerating system contemplated herein, the separate chambers A and B are maintained at different temperatures, and the flow of the refrigerant is effected through the instrumentality of a single rotary compressor having a double suction arrangement whereby both the high-pressure and low-pressure refrigerant from the respective

evaporators 14 and 17 return to such compressor through their separate return lines, and the full charge of the compressed refrigerant is discharged to the condenser 8. There are two closed refrigerant circuits, and a compressor and condenser, common to both circuits provided. Also the refrigerant is metered to the respective high-temperature and low-temperature evaporators 14 and 17 through capillary members 13 and 16 that are individual to the respective evaporators.

While this invention has been described in detail in its present preferred form or embodiment, it will be apparent to persons skilled in the art, after understanding the improvements, that various changes and modifications may be made therein without departing from the spirit or scope thereof. It is aimed in the appended claims to cover all such changes and modifications.

I claim:

20. A two - temperature refrigerating system comprising, in combination, a compressor, a condenser into which compressed refrigerant is discharged from said compressor, a first evaporator, a second evaporator, a refrigerant restrictor means connected to and disposed between said condenser and said first evaporator and having a passage of relatively small cross-section therethrough for said refrigerant, said first evaporator being adaptable to vaporize a portion of said refrigerant received by it, vapor conduit means connected between said first evaporator and said compressor whereby said vaporized portion of said refrigerant will be conveyed from said first evaporator to said compressor, check valve means interposed in said last mentioned conduit means adaptable to prevent oil or extraneous matter from working up into said first evaporator, refrigerant conduit means connected between said first evaporator and said second evaporator adaptable to convey to said second evaporator the remaining liquid refrigerant in said first evaporator, said last mentioned refrigerant conduit means including restrictor means having a relatively small cross-section therethrough for said refrigerant, said second evaporator being adaptable to vaporize said liquid refrigerant received by it, vapor conduit means connected between said second evaporator and said compressor whereby said vaporized refrigerant in said second evaporator will be conveyed to said compressor, and check valve means interposed in said last mentioned conduit means adaptable to reduce reexpansion volume of the refrigerant to a minimum.

25. A two - temperature refrigerating system comprising, in combination, a compressor, a condenser into which compressed refrigerant is discharged from said compressor, a first evaporator, a second evaporator, a refrigerant restrictor means connected to and disposed between said condenser and said first evaporator and having a passage of relatively small cross-section therethrough for said refrigerant, and refrigerant return conduit means connected between said first evaporator and said compressor whereby a portion of said refrigerant will be conveyed from said first evaporator to said compressor, refrigerant conduit means connected between said first evaporator and said second evaporator adaptable to convey to said second evaporator any remaining liquid refrigerant in said first evaporator and including refrigerant restrictor means having a relatively small cross-section therethrough for said refrigerant, and refrigerant return conduit means connected between said second evaporator and said compressor whereby said vaporized refrigerant in said second evaporator will be conveyed to said compressor.

3. A refrigerating system comprising, in combination, a compressor, a condenser into which compressed refrigerant is discharged from said compressor, a first evaporator and a second evaporator in series relationship, refrigerant restrictor means connected between said condenser and said first evaporator, said first evaporator being adaptable to vaporize a portion of said refrigerant received by it, vapor return conduit means connected between said first evaporator and said compressor and having check valve means interposed in said conduit means adaptable to prevent oil or extraneous matter from working up into said first evaporator, said second evaporator being adaptable to vaporize said liquid refrigerant received by it, and vapor return conduit means connected between said second evaporator and said compressor and having check valve means interposed in said last mentioned conduit means adaptable to reduce re-expansion volume of the refrigerant to a minimum.

4. A two-temperature refrigerating system comprising, in combination, a compressor, a condenser into which compressed refrigerant is discharged from said compressor, a high temperature evaporator, a low temperature evaporator, a refrigerant restrictor means connected to and disposed between said condenser and said high temperature evaporator and having a passage of relatively small cross-section therethrough for said refrigerant, said high temperature evaporator being adaptable to vaporize a portion of said refrigerant received by it, vapor conduit means connected between said high temperature evaporator and said compressor whereby said vaporized portion of said refrigerant will be conveyed from said high temperature evaporator to said compressor, check valve means interposed in said last mentioned conduit means adaptable to prevent oil or extraneous matter from working up into said high temperature evaporator, refrigerant conduit means connected between said high temperature evaporator and said low temperature evaporator adaptable to convey to said low temperature evaporator the remaining liquid refrigerant in said high temperature evaporator, said last mentioned refrigerant conduit means including restrictor means having a relatively small cross-section therethrough for said refrigerant, said low temperature evaporator being adaptable to vaporize said liquid refrigerant received by it, vapor conduit means connected between said low temperature evaporator and said compressor whereby said vaporized refrigerant in said low temperature evaporator will be conveyed to said compressor, and check valve means interposed in said last mentioned conduit means adaptable to reduce re-expansion volume of the refrigerant to a minimum.

5. A refrigerating system comprising, in combination, a compressor, a condenser into which

compressed refrigerant is discharged from said compressor, a first evaporator and a second evaporator in series relationship, refrigerant restrictor means connected to said condenser and said first evaporator and having a passage of relatively small cross-section therethrough for said refrigerant, said first evaporator being adaptable to vaporize a portion of said refrigerant received by it, vapor conduit means connected between said first evaporator and said compressor whereby said vaporized portion of said refrigerant will be conveyed from said first evaporator to said compressor and having check valve means interposed in said conduit means adaptable to prevent oil or extraneous matter from working up into said first evaporator, said second evaporator being adaptable to vaporize said liquid refrigerant received by it, vapor conduit means connected between said second evaporator and said compressor whereby said vaporized refrigerant in said second evaporator will be conveyed to said compressor and having check valve means interposed in said conduit means adaptable to reduce re-expansion volume of the refrigerant to a minimum.

6. In a two-temperature refrigerating system comprising a compressor, a condenser into which compressed refrigerant is discharged from said compressor, and a first evaporator and a second evaporator in series relationship, the combination of a refrigerant restrictor means connected to and disposed between said condenser and said first evaporator and comprising a member having a passage of relatively small cross-section therethrough for said refrigerant, of vapor return conduit means connected between said first evaporator and said compressor whereby vaporized portions of said refrigerant will be conveyed from said first evaporator to said compressor, of check valve means interposed in said last mentioned conduit means adaptable to prevent oil or extraneous matter from working up into said first evaporator, of vapor return conduit means connected between said second evaporator and said compressor whereby vaporized refrigerant in said second evaporator will be conveyed to said compressor, and of check valve means interposed in said last mentioned conduit means adaptable to reduce re-expansion volume of the refrigerant to a minimum.
